JOHN RAYMOND HAMILTON, OF ST. JOHN, NEW BRUNSWICK, CANADA.

STRAP AND FASTENER.

988,090.

Specification of Letters Patent. Patented Mar. 28, 1911.

Application filed January 18, 1909. Serial No. 472,885.

To all whom it may concern:

Be it known that I, JOHN R. HAMILTON, of St. John, in the Province of New Brunswick, Dominion of Canada, have invented 5 certain new and useful Improvements in Straps and Fasteners, of which the following is a specification.

The primary object of my invention is to produce an improved strap, preferably of 10 metal, wherein provision is made for uniting and securing together temporarily or permanently, as desired, the opposite ends thereof when the strap is bent or doubled upon itself so as to bring said ends together.

15 Another object is to produce fastening mechanism for uniting the terminals or parts of one or more objects, such as the ends of a strap, or the ends of a plurality of straps.

20 Another object is to produce fastening mechanism of a distinctive character, which may positively identify the article or articles to which it is attached and from which it cannot be removed or disengaged without 25 either destroying the fastening mechanism or so far mutilating or changing its appearance as to afford evidence that the fastening mechanism has been tampered with.

My strap may be made of different metals 30 and in a variety of shapes, weights, and sizes, and is applicable to numerous important and varied uses.

Not to attempt to enumerate all of the uses to which it may be applied, it is deemed 35 sufficient to specify that it may be employed as a paper fastener, a leg band for poultry, and a car door seal.

My device when made of light metal as in 40 paper fasteners may be readily applied by simple manipulation without the aid of a tool, or for heavier and rougher uses, as in car door seals, its bending may require the use of pliers. The force necessary to apply it, however, has nothing to do with the na- 45 ture of the invention itself, the distinctive features whereof are presented in the various forms of embodiment to which it may be reduced, and irrespective of the weight of metal in which those forms are embodied.

50 In the accompanying drawing, which constitutes a part of this specification, Figure I is a perspective view of a simple and preferred form of embodiment of my device, showing it of about the size and dimensions 55 suitable for a paper fastener, and in flat form before it is bent into service. Fig. II is a perspective view of the subject matter

of Fig. I, showing the strap bent to bring the tongue and slotted ends opposite each other and in position ready for engagement. 60 Fig. III illustrates upon an enlarged scale the engagement of the tongue and slotted end of the strap, as shown in Fig. II. Fig. IV is an end view of the subject matter of Fig. III illustrating the tongue bent down 65 upon the slotted end of the strap. Fig. V is a transverse section of the tongue, detached, illustrating the angularity of junction of its two sides and one of the projections formed in said angle. Fig. VI is a 70 longitudinal sectional view of a portion of the subject matter of Fig. III illustrating the engagement of the tongue and the slot lip. Fig. VII is a top plan view of the subject matter of Fig. IV. Fig. VIII is a front 75 elevation of a modified form of tongue, showing one provided with oppositely serrated edges instead of the feather slotted edge shown, for example, in Fig. III. Fig. IX is a perspective view similar to Fig. III 80 but illustrating a perfectly smooth and curved tongue with a slot curved to fit it. Fig. X is a view similar to Fig. VII illustrating the tongue shown in Fig. IX bent down upon the slotted end of the strap, and 85 illustrative of the manner in which it is expanded and kinked by bending to fill and grip the ends of the slot. Fig. XI is a plan view of a strap provided with a terminally disposed tongue as a substitute for 90 the struck up tongue shown in the previous figures. Fig. XII is a view similar to Fig. I showing a strap provided with a struck up tongue and tongue slot at each end. Fig. XIII illustrates a mode of applying the 95 strap shown in Fig. XII and of utilizing the tongue and the slot at each end thereof for fastening the ends of the strap together. Figs. XIV, XV, and XVI illustrate the strap shown in Fig. XII utilized as an 100 envelop closure in three different modes of application.

Referring to the numerals on the drawing, 1 indicates my strap, which being made preferably of flat flexible metal of any kind 105 and weight suitable and preferred for the use to which it is intended to be applied, is characterized by the presence near one end of a slot-engaging tongue 2, and near the other of a tongue-receiving aperture 3. The 110 three elements specified are present in every form of embodiment of my device whose modifications contemplate variations in the shape and disposition of the tongue and in

the shape and disposition of the aperture 3, which is made to receive the tongue when the strap is applied in service, the shape and dimensions of the body of the strap 1 being 5 variable at pleasure. The disposition of the tongue to the strap is susceptible of any desired variation. In all of the figures of the drawing except Fig. XI is shown a tongue which is cut out of the body of the strap 10 and struck up to a position substantially at right angles to it, in which position it presents itself for ready insertion into the aperture in the opposite end of the strap when said end of the strap is bent over and 15 brought into position to permit the tongue to enter the aperture. The tongue is preferably made, for reasons which will presently appear, angular in cross section, as shown in Fig. V, or curved in cross section, 20 as shown in Fig. IX, for example, that is the distance between the edges of the tongue is less than the width of the material of the tongue, and the aperture 3 is preferably a slot which is made to conform to the shape 25 of the tongue for whose accommodation it is provided. Whether the slot be angular, as clearly shown in Fig. I or on an enlarged scale in Fig. VII, or whether it be in the form of an arc, as shown in Figs. IX and X, 30 there is always present in it a slot lip 5 (see Fig. VI) which enters the concave side of the tongue and which may be utilized for engagement of projections upon the tongue extending toward it. Such projections 35 are indicated by the numeral 6, and may be formed, for example, by puncturing the metal of the tongue at intervals. The projections 6 afford by engagement with the slot lip 5 means for uniting the tongue end 40 of the strap to the slotted end thereof. In addition to or in lieu of such means for uniting the two ends of the strap, engaging means upon the opposite edges of the tongue may be employed. For example, feather 45 slits 7 in the tongue may be employed, as shown in Fig. III, or serrations 8, as shown in Fig. VIII.

It should be observed that while the slot and tongue connection with or without the 50 projections 6, the slot-engaging slits 7, or the serrations 8 perform the function of adjustably uniting the two ends of the strap, they are most readily adjustable when the tongue is of the smooth form shown in Fig. 55 IV, and that the security of permanent union is obtained by bending the end of the tongue down upon the slotted end of the strap, as shown, for example, in Fig. VII. As shown in that figure, the edges of 60 the tongue next adjacent to a bend 9 therein are expanded beyond the ends of the slot and serve to positively secure the ends of the strap together. This function is also developed by the serrations 8 in bending 65 the tongue, shown in Fig. VIII, down upon

the strap after it has passed through its slot. A smooth tongue 10 formed for engagement with an arc shaped slot 11 is shown in Fig. IX. The effect of bending the end of the tongue 10 upon the slotted end of the strap 70 after insertion of the tongue into its slot 11 is to force out the edges of the tongue into engagement with the ends of the slot, and to produce in the tongue, as shown in Fig. X, a kink 14. This kink is characteristic 75 of each form of my device, being shown at 9 in Fig. VII as well as at 14 in Fig. X, but in a less pronounced degree. It cannot be removed after being once formed in the tongue, and constitutes a means of security 80 wherever a permanent union is desired.

When once my device has been permanently attached to an object by the bending and kinking of the tongue it cannot be removed therefrom without destroying the 85 device, or without mutilating the kinked tongue in a way to constitute it into a telltale. This feature is of special value in certain applications of my device, as, for example, in car door seals and leg bands. For the 90 purpose of temporary adjustment, the smooth tongue, shown in Fig. IX, is best adapted before it is bent and kinked. Afterward it lends itself most effectively to permanency of adjustment. It may be observed in this connection that the slotted and serrated forms of tongue shown in Figs. 95 III and VII, for instance, are adjustable within their respective slots, provided that they do not effect a close fit transversely 100 therein. If the fit is a loose one, the tongue may be moved back and forth in its slot until it is bent and thereby secured by the spreading of the tongue. See Figs. IV, VII, and X. If the slotted or serrated tongue fit 105 its slot closely, or if the feathers defined by the slits 7 be spread before the tongue is inserted, it is not susceptible of reverse adjustment therein, but the slits or serrations afford in themselves means of engagement 110 with the ends of the slot that is substantially permanent.

In Fig. XI I show a slight modification of the form of embodiment of my invention, in which a strap 15 is provided at one end with a slot 16, and at the other with terminally disposed slot-engaging tongue 17, the respective shapes preferred of the tongue and slot being conformable to each other. The manner of coöperation of the tongue and slot is identical with that of the tongues and slots previously described. This form of strap being simple, light, and easy of application, especially adapts itself to use for a leg band, although its use for that purpose is not to be regarded as exclusive of the other forms of strap illustrated.

In Fig. XII, I illustrate a strap 18 which is provided at each end with a tongue, that at one end being indicated by the numeral

19 and that at the other by the numeral 20. These tongues are both preferably struck up from the body of the strap, thereby defining therein at one end an aperture 21 and at the 5 other end an aperture 22. Adjacent to the tongue 19 is a slot 23, and adjacent to the tongue 20 is a slot 24. The slots 23 and 24 are designed to accommodate the one or the other of the tongues. If, for instance, the 10 tongue 20 is designed to enter the slot 23, the tongue 19 will enter the aperture 22, and contrariwise. When the strap 18 is applied as a paper fastener, to which use it is especially adaptable, both the tongues 19 and 20 15 pass in opposite directions through the papers or the like which are to be secured together by them. When the ends that carry the two tongues are pressed toward each other, if the tongue 19 enters the slot 24, the tongue 20 will enter the aperture 21, as has been stated. Both tongues, after being passed through the papers and through a respective slot and aperture, may be then bent down upon the outside of the strap 18, as 20 shown at 25 and 26 in Fig. XIII, when the slot-engaging tongue will be kinked after the manner previously described with reference to the single tongued strap. In operation, therefore, the strap 18 affords a double and 25 secure fastening when applied as shown in Fig. XIII, with a security of permanent attachment equal to the single tongue fastener. The strap 18 is also susceptible of a convenient double use, being applicable, like a 30 staple, for closure of envelops, as suggested in the three different modes of its application 35 as a staple shown in Figs. XIV, XV, and XVI.

It is obvious that the fastening mechanism 40 employed for uniting the ends of my strap may be employed for uniting a plurality of objects which is, as specified, contemplated within the purview of my invention.

It is my purpose not to limit myself to the 45 exact details of construction herein shown and described, but to reserve the right to modify and vary the same within the scope of the invention as herein specified and defined in the appended claims.

50 What I claim is:

1. A flexible metallic strap in one piece, provided with a slot at one end, and a flexible slot-engaging tongue at the other, adapted to effect a union when the strap is bent 55 or doubled upon itself, so as to bring the tongue and slot into engagement, and means which is a part of the strap itself, provided for adjustably uniting the tongue and slot.

2. A flexible metallic strap in one piece, 60 provided with a slot at one end, and a flexible slot-engaging tongue at the other, adapted to effect a union when the strap is bent

or doubled upon itself so as to bring the tongue and slot into engagement, and means which is a part of the strap itself, provided 65 for adjustably uniting the tongue and slot, said means comprising slot-engaging means upon the tongue.

3. A flexible metallic strap in one piece, provided with a slot at one end, and a flexible slot-engaging tongue at the other, adapted to effect a union when the strap is bent or doubled upon itself so as to bring the tongue and slot into engagement, means which is a part of the strap itself, provided 75 for adjustably uniting the tongue and slot, said means comprising projections upon the tongue, and a slot lip for engagement of projections upon the tongue.

4. The combination with a strap provided 80 with a slot, of a flexible tongue upon the strap adapted to enter said slot when the strap is bent, and to be bent thereafter into permanent engagement with the strap, and means for permanently engaging the tongue 85 in the slot.

5. The combination with a strap provided 90 with a slot, of a flexible tongue fitting the slot and adapted to enter the same when the strap is bent to effect their engagement, the distance between the edges of said tongue being less than the width of the tongue, whereby, when the tongue is bent above the slot, as described, it will expand into secure engagement with the ends of the slot. 95

6. Fastening mechanism for uniting parts of one or more objects, which consists of the combination of one part provided with a slot, of another part provided with a slot-engaging flexible tongue, said slot and 100 tongue being fitted to each other, the distance between the edges of said tongue being less than the width of the tongue, whereby, when the tongue is bent above the slot, as described, it will form a permanent kink 105 in the tongue, substantially for the purpose specified.

7. A flexible metallic strap in one piece, provided with a slot near one end, and a slot fitting and engaging flexible tongue at 110 or near the other end adapted to effect a union when the strap is bent or doubled upon itself, so as to bring the tongue and slot into engagement, and means which are a part of the strap itself, provided for adjustably and permanently uniting the tongue 115 and slot.

In testimony whereof I have hereunto signed my name in the presence of two subscribing witnesses.

JOHN RAYMOND HAMILTON.
